UNITED STATES PATENT OFFICE.

ALBERT C. ROGERSON, OF CHICAGO, ILLINOIS, ASSIGNOR TO AUTOMATIC MOLDING MACHINE COMPANY, OF CHICAGO, ILLINOIS, A CORPORATION OF ILLINOIS.

MOLDING APPARATUS.

No. 874,440.

Specification of Letters Patent.

Patented Dec. 24, 1907.

Application filed November 17, 1905. Serial No. 287,806.

To all whom it may concern:

Be it known that I, ALBERT C. ROGERSON, a citizen of the United States, residing at Chicago, in the county of Cook and State of Illinois, have invented a new and useful Improvement in Molding Apparatus, of which the following is a specification.

My invention relates particularly to apparatus for use in preparing molds, cores and forms for use in casting metals; and my primary object is to provide simple and efficient means for more expeditiously and in an improved manner performing this task.

The invention is illustrated in its preferred embodiment in the accompanying drawings, in which—

Figure 1 is a view partly in section and partly in elevation of my improved apparatus; Fig. 2, a broken section taken as indicated at line 2 of Fig. 1; Fig. 3, a broken section taken as indicated at line 3 of Fig. 2 and showing an adjustable sand-impelling device, or packer, employed; Fig. 4, a section taken as indicated at line 4 of Fig. 3; and Fig. 5, a section taken as indicated at line 5 of Fig. 4.

In the construction illustrated, the apparatus comprises a hopper A for the molding sand; a horizontal screw conveyer B receiving the material from said hopper through an interposed reciprocating screen, or sifter, B¹, actuated by a shaft B²; an endless inclined elevator C receiving the material from the conveyer B; a horizontal screw conveyer D receiving the material from the elevator C; a shiftable impelling device, or packer, E, receiving the material from the conveyer D; a flask, F, into which the sand is discharged, with great force, from the packer; and driving means for the various operative parts, which will be presently described.

The details of construction may be variously modified and various parts may be omitted, according to circumstances and conditions. The apparatus, as illustrated, however, includes means for receiving the sand from the molds after use, sifting it, elevating it, and injecting it at high velocity and with great force of impact into the mold-box.

The essential features of the invention consists of a power actuated device, herein exemplified in the form of a packer belt, by means of which the sand is projected with

packing force into the mold box and which said device is disposed in and movable with a universally movable chute through which the sand is carried thereby, said projecting device delivering such sand directly into the mold box without previous contact with any surface which could possibly hinder or alter its speed of delivery the chute serving merely as a supporting frame for the projector and as a shield to prevent the escape of sand from the path thereof thus insuring that all sand is delivered to the mold box with equal force and further enabling the same to be projected in any desired direction so as to enable every portion of the mold box to be packed with uniform density and the sand to be uniformly and evenly distributed.

In order to secure the best results it is necessary that the sand be delivered in very small quantities following each other in rapid succession, it being observed that delivery thereof in large lumps or batches causes unevenness and lack of uniformity in density owing to the fact that such large lumps or batches are shattered by the impact and accordingly pack more firmly in the middle than at the edges.

The operative parts, in the construction shown, are operated from a shaft a, which is joined by belts a¹, a², a³, respectively, to the shaft B² actuating the screen, a shaft a⁴ actuating the conveyer B, and a shaft a⁵ from which the elevator C, conveyer D and packer E are actuated. The shaft a⁵ is joined by a belt a⁶ to a shaft a⁷ which is connected by gears a⁸ with the actuating shaft of the elevator C. The shaft a⁵ is equipped at one end with a friction disk a⁹, which communicates motion, through a shiftable friction disk a¹⁰, to a shaft a¹¹ parallel with and joined by a belt a¹² to the shaft a¹³ of the conveyer D. The shaft a⁴ has ordinary tight and loose pulleys a¹⁴, indicated by dotted lines, for receiving the belt a²; and the shaft a⁷ is equipped with tight and loose pulleys a¹⁵ for receiving the belt a⁶. The belts a² and a⁶ are supplied, respectively, with shifters a¹⁶, a¹⁷, of ordinary construction. These shifters and the friction disk a¹⁰ are actuated by a lever a¹⁸ joined by a link a¹⁹ to a hand-lever a²⁰. The belt-shifters are joined, by connections, a²¹, a²², a²³, a²⁴ and a²⁵ to the lever a¹⁸. The details are common and unimportant.

The packer E comprises a frame e suspended by a universal connection e¹, from the hanger e²; and an endless belt e³ passing about pulleys e⁴ at the upper and lower ends of the frame. The upper pulley is carried by a shaft e⁵ forming a part of the universal joint; and said shaft is equipped with a conical pulley e⁶ with which is connected a rope belt e⁷ driven by a pulley e⁸ on the shaft e⁵. The belt e³ works in channels e⁹, e¹⁰, with which the frame e is provided, and is equipped with blades, or cleats, e¹¹, which serve to engage the molding material. The channel e¹⁰ constitutes a chute or casing through which the sand is impelled by the blades and which serves to confine the sand and maintains the same within the path of said blades between the points of admission and discharge of said sand irrespective of the position of said casing. This chute or casing is joined by a flexible connection, such as canvas, e¹², to the adjacent end of the conveyer D. The connection is such as to form a passage without interfering with the free swinging movement of the packer. The belt e⁷ is controlled by a shifter e¹³, by means of which the speed of the belt e³ is regulated at will. The packer and attendant parts are shown supported on a vertically adjustable frame G, the adjustment of which, as by means of bolts g, serves to regulate the height of the free end of the packer, thereby accommodating the device to flasks of varying heights. The operation will be readily understood. The molding material is sifted, transferred through the conveyer B to the elevator C, raised by the elevator C to the conveyer D, thence transferred to the packer E, and by the packer injected with high impactive force, in a rapid succession of short streams, into the flask, or mold-box F. The mold-boxes for ordinary work, are supported on trucks (not shown) mounted on a track passing beneath the lower end of the packer. The attendant swings the packer, at will, to direct the issuing sand to all parts of the mold-box. The packer-belt e³ operates at high velocity, which may be changed to suit conditions, and experience has demonstrated, will operate to thoroughly pack the mold-box, with any desired degree of firmness, obviating all necessity for stamping, pressing or ramming. The work is done in a small fraction of the time heretofore required, and the material is caused to conform, with the utmost fidelity, to the outlines of the pattern, no matter how inaccessible the recesses of the pattern under known methods of treatment. As has been stated, the operation of the conveyers and elevator is controlled by the lever a²⁰, which is conveniently located with reference to the packer, so that the delivery of sand can be controlled at will. So, also, the speed of the packer-belt is controlled by the conveniently located belt-

shifter e¹³. As stated, the height of the packer with relation to the mold-box may be adjusted at will.

While apparatus constructed in detail as described is admirably adapted to the purpose, no limitation in matters of detail is to be understood from the description.

It is expected that the free end of the movable packer may be pointed in any direction, and it is only for illustration that downward, as distinguished from lateral, delivery, is indicated.

What I regard as new, and desire to secure by Letters Patent, is—

1. In molding apparatus, power actuated sand projecting means, a pivotally - suspended frame carrying the same, means for feeding sand into the path of said projecting means, and means for maintaining said sand in such path between the points of admission and discharge.

2. In molding apparatus, power actuated sand projecting means, a pivotally - suspended universally movable frame carrying the same, means for feeding sand into the path of said projector, and means for maintaining the sand in such path between the points of admission and discharge thereof.

3. In molding apparatus, power actuated sand projecting means, a pivotally - suspended frame carrying the same, means for feeding sand into the path of said projecting means, means for maintaining said sand in such path between the points of admission and discharge, and means for varying the speed of said projecting means.

4. In molding apparatus, power actuated sand projecting means, a pivotally - suspended universally movable frame carrying the same, means for feeding sand into the path of said projecting means, means for maintaining said sand in such path between the points of admission and discharge, and means for varying the speed of said projecting means.

5. In molding apparatus, a suspended packer comprising a freely movable laterally shiftable casing, and power actuated sand projecting means disposed within said casing and serving to deliver the sand at high velocity into a mold box.

6. In molding apparatus, a suspended packer comprising a casing movable laterally in all directions, and power actuated sand projecting means carried by said casing and movable therewith, said projecting means delivering the sand directly to a mold box.

7. In molding apparatus, a suspended packer comprising a casing movable laterally in all directions, and a traveling power actuated carrier carried by said casing and serving to impart high velocity to the sand to project the same with packing force into a mold box.

8. In molding apparatus, a suspended

5 packer comprising a freely movable, laterally-shiftable casing, and a moving endless packing belt moving within said casing for imparting high velocity to the molding material.

9. In molding apparatus, a suspended packer comprising a casing freely movable laterally in all directions to enable it to be directed towards any part of a mold-box, 10 and a suitably actuated packing belt moving within said casing and serving to impart high velocity to the molding material.

10. In molding apparatus, the combination with a source of sand supply, of a 15 packer comprising a swinging frame capable of swinging in all directions provided with a casing and equipped with pulleys, an endless paddle equipped belt supported on said pulleys and moving through said casing, and 20 means for actuating said belt.

11. In molding apparatus, the combination with a source of sand supply, of a packer comprising a frame having a universal supporting joint and a pulley-equipped shaft at 25 said joint, a pulley at the free end of the frame, a casing carried by the frame, an endless belt passing over said pulleys and moving through said casing and provided with 30 paddles, and means for rotating said first-named shaft, for the purpose set forth.

12. In apparatus of the character set forth, the combination of a sifter, a sub-

stantially horizontal conveyer into which the sand is discharged by the sifter, an elevator, a substantially horizontal conveyer 35 receiving the material from the elevator, a packer-frame having a casing flexibly connected with said last-named conveyer, a packer-belt mounted on said frame and moving through said casing, and means for 40 actuating the operative parts.

13. In apparatus of the character set forth, the combination of a movable packer-frame equipped with a casing, a packer-belt operatively mounted on said frame and moving in said casing, mechanism for delivering sand to said casing and controlling means 45 equipped with a handle located near said casing, whereby the operator may guide the packer and control the delivery of sand, for 50 the purpose set forth.

14. In apparatus of the character set forth, the combination of a packer mounted to permit it to swing, a conveyer serving to deliver material to the packer, an elevator 55 serving to deliver material to said conveyer, and common controlling means for said conveyer and elevator located adjacent to the packer within reach of an operator guiding the packer.

ALBERT C. ROGERSON.
